S. G. GOSS,
OPERATING MECHANISM FOR INK ROLLERS,
APPLICATION FILED JUNE 16, 1916.

1,225,800.

Patented May 15, 1917.

UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

OPERATING MECHANISM FOR INK-ROLLERS.

1,225,800.

Specification of Letters Patent.

Patented May 15, 1917.

Application filed June 16, 1916. Serial No. 103,944.

To all whom it may concern:

Be it known that I, SAMUEL G. Goss, a citizen of the United States, and a resident of Glencoe, in the county of Cook, State of Illinois, have invented certain new and useful Improvements in Operating Mechanisms for Ink-Rollers, of which the following is a specification, reference being had to the accompanying drawing.

10 My invention relates to operating mechanisms for ink rollers and has for its principal object the provision of a differentially-acting inking mechanism whereby the amount of ink delivered to the inking cylinder is greater relative to the speed of the press when the press is being driven at low speed or is being brought up to its high speed operation than when the press is driven at its normal high speed. To this end it is one of the objects of my invention to provide for driving the fountain roller differentially. It is another object of my invention to improve mechanisms of this type in sundry details hereinafter pointed out. The preferred means by which I have accomplished my several objects are illustrated in the drawings and are hereinafter specifically described. That which I believe to be new and desire to cover by this application is set forth in the claims.

In the drawings:

Figure 1 is a fragmentary view showing a part of a printing press embodying one form of my improved roller driving mechanism;

Fig. 2 is a vertical section through my improved device, being substantially a section taken on line 2—2 of Fig. 1;

Fig. 3 is a fragmentary view similar to Fig. 1, but showing a modified form of roller driving mechanism; and

Fig. 4 is a view of the mechanism at the end of the inking cylinder in Fig. 3 as seen from the right in said figure.

45 Referring to Figs. 1 and 2 in which corresponding parts are indicated by the same reference characters,

10 indicates the framework of a press having an inking cylinder 11 revolvably mounted thereon. An oscillating roller 12 is actuated by any suitable means not shown for transferring ink from a fountain-roller 13 to the inking cylinder 11, the inking roller

13 being adapted to take ink from the fountain 14 by rotation therein upon its shaft 55 13^a, as is readily understood.

The fountain-roller 13 is normally driven by a pawl 15 mounted upon a pivotally mounted arm 16 and adapted to engage a ratchet wheel 17 fixed upon the shaft 13^a 60 of the fountain-roller 13. The arm 16 is oscillated, in the construction shown, by means of a link 18 connecting the lower end of the arm with a disk 19 eccentrically thereof, the disk 19 being adapted to be driven in timed 65 relation to the speed of the press by means of a shaft 20 driven from any suitable portion of the press.

Revolvably mounted upon the shaft 13^a of the fountain-roller 13 is a shroud-plate 21 70 provided with an arm 22 extending laterally therefrom. The arm 22 is connected by means of a link 23 to a governor 24 of any suitable type which is adapted to be rotated by a shaft 25 preferably driven in timed relation to the speed of the press. The form of governor shown comprises a head 26 slidably mounted upon the upper end of the shaft 25, the head 26 being connected to the link 23 so as to revolve thereabout but so 75 as to be held against movement longitudinally thereof. The head 26 is connected with the shaft 25 through the medium of weighted links 27 which are adapted to move outward against the action of a spring 80 28 under the actuation of the centrifugal force developed by the weighted links 27.

With the shafts 20 and 25 being driven at slow speed in timed relation to the low speed driving of the press, the shroud 21 90 will be turned substantially to the limit of its movement in counterclockwise direction in Fig. 1, in which position the shroud has little or no effect upon the action of the pawl 15. As the shafts 20 and 25 are speeded up, however, when the press is attaining its full-speed driving, the weighted links 27 are forced outward by centrifugal force against the action of the spring 28, drawing the head 26 downward and turning the 100 shroud 21 in clockwise direction in Fig. 1. The shroud 21 in such turned position serves to render the pawl 15 ineffective for a portion of its stroke, thus serving upon an increase in the speed of the press to decrease 105 the relative speed of the fountain-roller 13.

Referring now to Figs. 3 and 4 which show the modified form of roller driving mechanism, 29 indicates a worm-gear fixed upon the shaft 13^a of the fountain-roller 13. Meshing with the worm-gear 29 is a worm 30 mounted upon a shaft 31 provided with a ratchet-wheel 32. Revolubly mounted upon the shaft 31 are two arms 33—34 provided with pawls 35—36, respectively, adapted to act simultaneously upon the ratchet-wheel 32. The arms 33—34 are connected by means of links 37—38 with a driving wheel 39 fixed upon a shaft 40 which is driven preferably in timed relation to the speed of the press by any suitable means. The links 37—38 are connected to the driving wheel 39 by means of a bell-crank lever 41 one arm of which bears a weight 42. A spring 43 tends to hold the weight moved to the limit 20 of its motion toward the shaft 40. When the shaft 40 is driven at a slow speed corresponding to the slow speed operation of the press, the weight 42 will be held by the spring 43 substantially in the position shown in Fig. 4 whereby the lower ends of the links 37—38 are held in their outermost position relative to the shaft 40. When the shaft 40, however, is being brought to its high speed rate of rotation, the weighted 25 arm 42 of the bell-crank lever is forced by centrifugal force away from the shaft 40 against the action of the spring 43 bringing the lower ends of the links 37—38 closer to the shaft 40. As will be readily understood, when the links are moved closer to the shaft 40 and maintained in such position, the extent of movement of the arms 33—34 is correspondingly decreased as actuated through the medium of the links, in this way serving 30 to diminish the driving effect of the pawls 35—36 upon the ratchet-wheel 32 and consequently upon the fountain-roller 13.

By the use of my invention, by which a differential driving of the inking mechanism is secured, a comparatively great amount of ink is fed during the low speed rotation of the press preparatory to an operative run of the press. The inking mechanism is accordingly brought very quickly to a completely 35 inked up condition, by reason of which it is unnecessary to run the press for any considerable time for obtaining a properly inked product. The result is that there is a very considerable saving in paper, inasmuch as a poorly inked product is not available for use. While the mechanism as shown provides for an increased speed of operating the inking mechanism during the operation of starting the press and bringing it to its 40 high speed operation, my improved mechanism also is capable of differentiating as is required in case the press is for any reason driven at one time in operation more rapidly than at another, serving to deliver an increased amount of ink in proportion to the

requirements rather than in proportion to the increase in the speed of driving the press.

What I claim as my invention and desire to secure by Letters Patent, is—

1. In a printing press, the combination of an inking mechanism, and means for driving said inking mechanism, comprising means serving upon an increase in the speed of the press to decrease the speed of the inking mechanism relative to that of the press. 75

2. In a printing press, the combination of an inking mechanism, and means driven in timed relation to the speed of the press adapted to drive said inking mechanism at a differential speed, serving upon an increase in the speed of the press to decrease the speed of the inking mechanism relative to that of the press. 80

3. In a printing press, the combination of an inking mechanism, and means for driving said inking mechanism in timed relation to the speed of the press, adapted when the press is being driven at its low speed and when the press is being brought up to its high speed to drive the inking mechanism at a comparatively higher speed relative to that of the press than when the press has attained its normal high speed rotation. 85

4. In a printing press, the combination of an inking mechanism, and means for driving said inking mechanism in timed relation to the speed of the press, comprising a governor driven in timed relation to the speed of the press adapted upon an increase in the speed of the press to decrease the speed of the inking mechanism relative to that of the press. 95

5. In a printing press, the combination of an ink-fountain, a fountain-roller revolubly mounted in said fountain, and means for rotating said fountain-roller, comprising means serving upon an increase in the speed of the press to decrease the speed of rotation of the fountain-roller relative to that of the press. 105

6. In a printing press, the combination of an ink-fountain, a fountain-roller revoluble in said fountain, means driven in timed relation to the speed of the press for rotating said fountain-roller, and means serving upon an increase in the speed of the press to cause said driving means to rotate said fountain-roller at a comparatively slower speed relative to that of the press. 115

7. In a printing press, the combination of an ink-fountain, a fountain-roller revoluble in said fountain, a ratchet-wheel revoluble with said fountain-roller, a pawl engaging said ratchet-wheel, means for reciprocating said pawl in timed relation to the speed of the press, and means controlled by the speed of the press for limiting the engagement of the pawl with the ratchet-wheel adapted upon an increase in the speed of the press 125

to decrease the speed of the fountain roller relative to that of the press.

8. In a printing press, the combination of an ink-fountain, a fountain-roller revoluble in said fountain, a ratchet-wheel revoluble with said fountain-roller, a pawl engaging said ratchet-wheel, means for reciprocating said pawl in timed relation to the speed of the press, a shroud adapted to be moved for 10 limiting the engagement of the pawl with the ratchet-wheel, and means controlled by the speed of the press for controlling the position of the shroud whereby upon an increase in the speed of the press the speed of 15 the fountain-roller is decreased relative to that of the press.

9. In a printing press, the combination of an ink-fountain, a fountain-roller revoluble in said fountain, a ratchet-wheel revoluble 20 with said fountain-roller, a pawl engaging said ratchet-wheel, means for reciprocating said pawl in timed relation to the speed of the press, a shroud adapted to be moved for limiting the engagement of the pawl with 25 the ratchet-wheel, a governor driven in timed relation to the speed of the press, and connections between said shroud and said governor whereby said governor is adapted upon an increase in the speed of the press to 30 move said shroud for decreasing the effective stroke of said pawl relative to said ratchet-wheel for correspondingly decreasing the rotation of the fountain-roller relative to the speed of the press.

25 10. In a printing press, the combination

of an inking mechanism, and means for driving said inking mechanism in timed relation to the speed of the press, comprising a governor driven in timed relation to the speed of the press adapted when the press is 40 being driven at its low speed and when the press is being brought up to its high speed to drive the inking mechanism at a comparatively high speed for bringing the inking mechanism quickly to effective operation and 45 adapted when the press has attained its normal high speed rotation to drive the inking mechanism at a comparatively slower speed.

11. In a printing press, the combination of an inking device, a variable speed mechanism for driving said inking device, and means controlled by the speed of the press for controlling the speed of driving through 50 said variable speed mechanism.

12. In an inking mechanism for printing 55 presses, the combination of an inking device, and means for driving said inking device, comprising means serving upon a variation in the speed of the press to differentially vary the speed of the inking device relative 60 to that of the press.

13. In an inking mechanism for printing presses, the combination of an inking device, means driven in timed relation to the speed of the press for operating said inking device, 65 and means serving upon a variation in the speed of the press to cause said driving means to operate said inking device differentially relative to the speed of the press.
